UNITED STATES PATENT OFFICE.

ISIDOR EPHRAIM, OF COLLEGE POINT, LONG ISLAND, NEW YORK.

SOFT-TIP LADY'S HAT LINING.

Application filed November 22, 1922. Serial No. 602,584.

To all whom it may concern:

Be it known that I, ISIDOR EPHRAIM, a citizen of the United States, and a resident of College Point, Long Island, in the county of Queens and State of New York, have invented a new and Improved Soft-Tip Ladies' Hat Lining, of which the following is a full, clear, and exact description.

This invention aims to provide an improved lining for use in the crowns of ladies' hats, characterized by a one-ply thickness of a fibrous woven or knitted material comprising two members, a band or side piece, and a crown or tip, permanently stitched together to form the complete lining before the latter is stitched or otherwise mounted in place in the hat.

Specifically, the invention aims to provide certain improvements over the lining of such completely preformed type disclosed in U. S. Letters Patent No. 1,216,140 to Kurtz. The nature of the construction there described and the subsequent commercial history of such construction should here be given, to explain the objects and advantages of the present invention. According to the description of that patent as to the location of the line of stitching joining the periphery of the tip and the periphery of the upper end of the band, said patent is merely representative of practice prior thereto in the art of making linings of the kind indicated for ladies' hats, the claims of said patent being both limited to the interposition at such line of stitching of what is termed an "uncovered cord" to make "an ornate seam." Thus this patent, as to the relative shapes of the patterns according to which tip and band are cut from the material used, such material generally being silk, satin, sateen or the like, calls for a band which is of substantially the same diameter at both ends of the sleeve-like body established by such band before band and tip are stitched together, and consequently calls for a tip of less diameter than the diameter of the sleeve-like body. This reduced diameter for the tip is required because it has long been known that it is necessary in preforming such linings to provide a circumferential piece of material intermediate the opposite ends of the lining to be shirred to establish an arching of the lining all around at such intermediate zone to adapt the finally preformed lining to fit more or less closely the substantially hemispherical concavity at the upper in-

terior of the hat crown. Therefore, necessarily according to the unclaimed disclosure of said patent and the prior constructions analogous thereto, in regard to the shapes and relative dimensions of band and tip, the complete lining could only be preformed to have such arched portion as the result of a gathering or shirring operation relative to the upper or tip-adjacent marginal portion of the band. Practically, however, it has been found that such a shirring of the band material, even with the patented cord above mentioned, is not practicable commercially in a lining having tip and band both of one-ply material, due to the inability to hold the tip properly stretched during the stitching and shirring operation which is required to join band and tip. As a result, the market is now supplied with a lining according to said patent in which the tip is of two-ply thickness, one of which plies of material is the usual light weight piece of silk, satin, sateen or the like, and the other ply of which is of thicker, stiffer, and heavier material. According to this construction, the lining of said patent may be manufactured commercially; but the troubles cured by the presence of the auxiliary heavier ply aforesaid are thus cured at the cost of a serious resulting disadvantage, which it is the object of the present invention to overcome. Such disadvantage, in the previous lining just described and having a two-ply tip element, is the fact that the finally preformed lining must be mounted in a woman's hat according to the requirement of the consumer. Such requirement is that the complete lining be mounted in the crown of the hat solely as the result of stitching the lining in place in the hat at points along a line or lines below the middle girth of the band, that is, near the line of joining of crown and brim of the hat. But when a complete lining having a two-ply tip as desired is so mounted in the hat, the weight of the tip is such that the minute fibre projections from the exterior surfaces of the lining heretofore sufficient to maintain the latter in the hat crown fail to cause the lining to cling to the hollow of the crown, and on lifting a hat with the crown uppermost the lining falls out of place bellying downwardly below the brim level.

I have discovered that such disadvantage may be overcome in a lining of one-piece thickness for both tip and band, and yet

band and tip may be stitched together easily and quickly and at nominal cost to provide a hat lining having the required arch all around, and accordingly the object of the present invention may be attained simply as the result of rearranging the relative dimensions of band and tip and correspondingly relocating the line of stitching joining the same, while preferably using an interponent of a different cross-sectional characteristic than the cord proposed by said patent. This interponent is a flexible elongate strip, having, however, dissimilar lateral dimensions, that is, being of greater width than thickness; which interponent may be a length of ribbon, tape, braid, or any flat elongate piece of material, but preferably one with at least one selvaged edge. The interponent of the present invention is thus preferably used to facilitate the construction of the new lining to provide the required arched portion according to the principle of the present invention, that is, as the result of gathering or stirring the marginal portion of the tip all around while avoiding entirely any gathering or stirring of the marginal portion of the band to be joined to the tip, and while cutting such band from a pattern having parallel straight sides rather than arcuate sides as is customary in the art of making linings for men's hats of the stiff-felt-crown type and where the lining is glued or stitched at various tip portions to the interior of the hat crown. This patterning of the band as described is important, because otherwise the band will not be a tubular member of substantially constant diameter from top to bottom as is required for ladies' hats to allow for various coiffures. The manufacture of the lining of the present invention is further facilitated by the use of the tape-like interponent preferably employed, because such interponent may be easily and quickly stitched to the gathered or stirred marginal portion of the tip when such tip is so gathered or stirred before stitching tip and band together; and in such case, which is recommended, a feature of the present invention is the use of two lines of stitching at the junction of band and tip, rather than merely one as in said patent; the first applied line of stitching joining tip and strip and simultaneously gathering or stirring tip and strip, and the second applied line of stitching joining band and tip and preferably also piercing the strip.

The invention will be more clearly understood from the following description, when taken in connection with the accompanying drawing illustrating an embodiment of the invention as at present preferred, in which drawing:

Figs. 1, 2, 3 and 4 are more or less diagrammatic views graphically indicating the salient distinctions between tip and band of

said patent and tip and band of the present invention, Fig. 1 being in the nature of a perspective view, Fig. 2 being in the nature of a plan view, and Figs. 3 and 4 being in the nature of axial sections; and Fig. 5 is an axial sectional view illustrating the details of construction of tip and band of the present invention incorporating the interponent aforesaid.

Referring first to Figs. 1 to 4, the element 6 may be taken as representing the band before being attached to the tip. This band is cut from a piece of silk, satin, sateen or the like, pursuant to a pattern having straight parallel sides, so that the band, when its opposite ends are joined by any suitable stitched seam (not shown), is truly cylindrical and not conformant to the side wall of the frustum of a cone. The band 6 of Fig. 1 may represent either the band of the patent aforesaid or the band of the lining of the present invention.

Fig. 2 shows such band in top plan at the line 6; but in this view the dot-and-dash lines 7 indicate the periphery of the new tip, after the same is gathered or stirred as above described, while the line 8 indicates the periphery of said tip before such gathering or stirring. On the other hand, as will be seen from what follows in describing the details of Fig. 3, or rather in contrasting the details of Figs. 3 and 4, the line 7 of Fig. 2 represents also the unshirred periphery of the tip of said patent, and also the periphery of the upper end of the band of said patent after the same is stirred.

Thus, referring now to Figs. 3 and 4, the former illustrates the characteristic cross-section of the lining of said patent, while the latter illustrates the characteristic cross-section of the lining of the present invention. As a lining is shown in Fig. 3, then, the band is shown at 6^a, the stirred arch portion at 7^a, the tip at 8^a and the stitching joining band and tip at 10^a. And as a lining is shown in Fig. 4, the band is shown at 6^b, the arch portion at 9^b, the tip at 8^b, and the stitching joining band and tip at 10^b.

It will therefore be seen that whereas in the lining of said patent, the arch portion is a part of the band and the line of stitching which joins band and tip is located above the arch portion, as in Fig. 3, in the lining of the present invention the arch portion is a part of the tip and the line of stitching joining band and tip is located below the arch portion, as in Fig. 4.

Fig. 5 should now be examined, which shows more clearly the details of construction of the present lining, as well as the preferred presence of the interponent of strip material. In this view, the band is indicated at 6^b, the tip at 8^b, the arch portion of the latter at 9^b, and the preferably employed interponent at 11. As illustrated, the outer

marginal portion of the tip is Shirred as indicated at 12 to establish such arch portion. Arch portion 9^b is preferably established before the tip is attached to the band by a line of 5 stitching 13, which latter also serves to attach the preferably incorporated interponent 11 to the tip. If such interponent is a strip of silk ribbon, and shirred slightly also during the operation of applying the gathering 10 stitches 13, the decorative appearance of the lining when finished and mounted in the hat will be greatly enhanced; it being appreciated in this connection, of course, that the parts as drawn in Fig. 5 show the complete 15 lining but arranged inside out as in the course of making up the same. It will be understood that when the parts are arranged as shown in Fig. 5, and the interponent 11 is used, the single line of stitching 13 may be 20 employed to attach all three elements together. Preferably, however, and most decidedly so, because otherwise the main object of the present invention will not be served, a second line of stitching 14 is subsequently 25 used for joining band and tip as shown clearly in Fig. 5.

What I claim as new and desire to secure by United States Letters Patent is:

1. As a new article of manufacture, a flexible lining for the crowns of ladies' hats, including tip and band members of one-ply flexible material stitched together along a circumferential line, the band being of substantially the same diameter at top and bot-

tom, and the tip being a substantially circular piece shirred around its marginal portion to present a dished top. 35

2. As a new article of manufacture, a flexible lining for the crowns of ladies' hats, including tip and band members of one-ply 40 flexible material stitched together along a circumferential line, the band being of substantially the same diameter at top and bottom, and the tip being a substantially circular piece shirred around its marginal portion 45 to present a dished top, and a flexible strip of greater width than thickness interposed and secured in place between tip and band.

3. As a new article of manufacture, a flexible lining for the crowns of ladies' hats, including tip and band members of one-ply 50 flexible material stitched together along a circumferential line, the band being of substantially the same diameter at top and bottom, and the tip being a substantially circular piece shirred around its marginal portion to present a dished top, and a flexible 55 shirred strip of greater width than thickness and stitched longitudinally to the lining and interposed in place between tip and band. 60

4. The lining defined in claim 3, wherein said strip is secured to the shirred edge of the tip by a single circumferential line of stitching, and the strip, tip and band are secured together by a second circumferential line of stitching.

ISIDOR EPHRAIM.
